United States Patent Office.

AUGUSTUS RUOFF, OF DETROIT, MICHIGAN.

Letters Patent No. 93,481, dated August 10, 1869.

IMPROVEMENT IN METALLIC BUNGS WITH AUTOMATIC VENT.

The Schedule referred to in these Letters Patent and making part of the same.

To whom it may concern:

Be it known that I, AUGUSTUS RUOFF, of Detroit, in the county of Wayne, and State of Michigan, have invented a new and useful Improvement in Metallic Bungs, with Automatic Vents, for barrels; and I do declare that the following is a true and accurate description thereof, reference being had to the accompanying drawings, and to the letters of reference marked thereon, and being a part of this specification.

Figure 1 is a perspective view of my invention.

Figure 2 is a vertical sectional view of the same, on the line X X in fig. 1.

Like letters indicate like parts in each figure.

The object of this invention is to construct a metallic bung, provided with a self-acting vent, principally intended for beer or ale-casks, but which can be equally well applied to all casks designed for holding liquids.

It is well known that the bungs in common use are made from wood, which require to be replaced nearly every time a cask is filled, causing great expense to the brewer. The retailer or consumer is obliged to bore a hole through the wooden bung, and provide the same with a tightly-fitting plug. The hole is intended to admit a sufficient amount of air, that by its pressure, will compel the contents of the cask to escape through the faucet when opened for the purpose. When the draught is completed, the plug must be inserted into the hole to prevent the escape of the gas of the beer, and thereby obviate the tendency of the beer to become flat and spoiled. It frequently happens, that to make the wooden bungs tight in the cask, they are hammered in with great force, the concussion breaking off the resin with which the inside of beer-casks is covered, by means of which the beer would be spoiled.

In order to prevent loss, and save expense and trouble, I construct an annular ring, A, of any suitable material, provided with flange B.

This ring A is also provided around its periphery with a suitable thread, C, by means of which it may be screwed tightly into a suitable bung-hole in a cask.

The inner side of said ring is provided with another thread, which engages with a corresponding thread

upon the periphery of the bung D, which is provided, upon its lower side, with a lug, E, through which is bored the vent-hole F, which, at its upper end, connects with channel G, which leads to the top of the bung.

The end of the stud is covered by a strip of leather, India rubber, or other suitable material, H, which is wide enough to cover the vent-hole F, while its ends may be secured to the stud in any desirable or convenient manner.

The annular ring A is to be screwed into the bung-hole of a barrel or cask, and will remain there as long as the cask is serviceable.

When the cask has been filled, the bung D is screwed into the ring A, with rubber, or leather, or other suitable packing I, between the flange of the bung and proper seat in the ring to make the connection air-tight. This bung remains unchanged until the cask is emptied and returned to the brewery for cleaning and being refilled.

When the consumer or retailer draws off the beer, the pressure of the atmosphere passing through the vent, hereinbefore described, opens the valve H sufficiently to afford the required pressure upon the beer to compel it to run off through the proper faucet; and as soon as that is closed, the valve H contracts, and stops the vent.

These rings and caps should be made of uniform size, and with the same thread, so that any of the bungs will fit any of the rings, and they will outwear the casks, and may be used for a new one when the old cask is worn out.

A key, J, or any other suitable device, may be used in screwing my bung to place.

What I claim as my invention, and desire to secure by Letters Patent, is—

As a new, cheap, and superior article of manufacture, the metallic bung with automatic vent, herein described, consisting of the annular ring A, the bung D, provided with vent-hole F, and valve H.

AUGUSTUS RUOFF.
